Primary Examiner — Mark Goodwin(74) *Attorney, Agent, or Firm* — Waddey & Patterson, P.C.; Lucian Wayne Beavers(57) **CLAIM**

What is claimed is the ornamental design for a body panels for a construction machine, as shown and described.

DESCRIPTION

FIG. 1 is a right rear perspective view of the body panels for a construction machine showing our new design. The area within the four sided broken line boundary on the top body panel forms no part of the claimed design. The broken line showing of a construction machine in all the figures are for environmental purposes only and form no part of the claimed design.

FIG. 2 is a left rear perspective view thereof.

FIG. 3 is a right side elevation view thereof.

FIG. 4 is a left side elevation view thereof; and,

FIG. 5 is a rear perspective view thereof.
